SURFACING OF INKING ROLLS

Bruce W. Hubbard, Oak Park, Ill., assignor to
Ideal Roller & Manufacturing Co. Inc., Chicago,
Ill., a corporation of Illinois

Application August 29, 1932, Serial No. 630,844

5 Claims. (Cl. 91—46)

This invention relates to the coating of cylindrical inking rolls for printing presses to form a film of printing composition on the surfaces thereof.

5 The general aim of the invention is to provide a new and improved method of applying the composition to a roller surface which insures the formation of a coating of approximately uniform thickness over all parts of the surface, which may be carried out with simple and inexpensive apparatus by unskilled workmen and with a minimum amount of composition maintained in molten state.

10 In carrying out this object, the invention contemplates the maintenance of molten composition in a layer of substantially uniform thickness through which the roller to be coated is passed in an endwise direction and at a substantially uniform rate so that equal amounts of composition will be applied to different unit areas of the 15 surface and such areas will be heated to the same degree by the molten composition.

Another object is to provide a novel apparatus in which the above process may be carried out.

20 The invention also resides in the novel manner of applying molten composition so as to prevent the occurrence of air bubbles in the film of composition on the roller surface.

25 Other objects and advantages of the invention will become apparent from the following detailed description taken in connection with the accompanying drawing, in which

30 Figure 1 is an elevational view of apparatus for coating inking rolls in accordance with the present invention.

35 Fig. 2 is an enlarged fragmentary sectional view of a portion of the apparatus shown in Fig. 1.

Fig. 3 is a fragmentary elevational view of a 40 part of the coating apparatus.

Fig. 4 is a fragmentary perspective view of a part of the coating apparatus.

45 With the apparatus shown in the drawing, each roller 5 to be surfaced is disposed in vertical position during coating and the molten composition is applied throughout the length of the roller by effecting relative vertical movement between the roller and a receptacle 6 adapted to contain a layer of composition surrounding the periphery of the roller. Preferably, such movement is obtained by raising the roller which may be suspended from a cable 7 coupled to one end trunnion 8 of the roller and extending around a pulley 9 and thence around a winding drum 10 50 driven through appropriate speed-change mech-

anism by a reversible and constant speed driving means such as an electric motor 11. The hoisting mechanism thus employed may be supported by a vertical post 12 pivoted to swing laterally between the coating position shown in full lines in Fig. 1 and an unloading position shown in dotted outline.

5 The receptacle 6 may be relatively shallow and preferably has a bottom wall 13 converging toward a central opening through which the roller extends during coating. Around said opening is a ring 14 of flexible material such as rubber and of such size as to bear against the periphery of the roller and provide an effective seal therearound while at the same time permitting the 15 roller to be drawn upwardly through the composition in the receptacle.

10 The composition to be used in coating is melted and maintained at a substantially uniform temperature in a water-jacketed tank 15 which preferably is relatively small and deep so that the 15 volume of composition required to be kept in storage is reduced to a minimum. Molten composition from the tank is delivered at a uniform rate of flow to the receptacle 6 which, in the form 20 shown in Fig. 1, is accomplished by a constant discharge pump 16 driven by an electric motor 17. For this purpose, the pump inlet communicates with an outlet 18 at the bottom of the tank and the outlet communicates through a pipe 19 25 with the receptacle 6 at a point below the normal level of the liquid therein. The rate of flow of composition to the receptacle may be varied by manipulating a valve 20 thereby causing more or less of the composition delivered by the pump 30 to be by-passed back into the tank through a pipe 21.

35 Since the composition is delivered to the pump under pressure and discharged into the receptacle below the level of liquid therein, the possibility of air bubbles becoming entrapped in the composition in the receptacle or in the film retained on the roller surface is entirely eliminated. Air bubbles may also be eliminated with the 40 gravity feed system shown in Fig. 3 wherein the tank 15 is placed above the receptacle 6 and the flow of composition to the latter regulated by a valve 22.

45 Owing to the inherent physical nature of the composition employed, the formation of a film 50 of uniform thickness throughout the length of the roller is dependent to a large extent upon the uniformity with which the successive longitudinal sections of the roller are heated in passing upwardly through the layer of composition in the 55

receptacle 6. It will be apparent that uniformity in heating will obtain when the roller is raised at a uniform speed and the liquid in the receptacle is maintained at a substantially constant level. This latter condition exists in the present system by virtue of an overflow pipe 23, the inlet opening of which is placed at the desired height above the receptacle inlet and adapted to be regulated in size by a valve member 24. During 10 coating, the pump is adapted to deliver to the receptacle a quantity of molten composition in excess of that required for coating the roller and such excess overflows through the pipe 23 and is returned to the tank 15.

15 To catch the composition discharged downwardly through the receptacle opening when the lower end of the roller passes out of engagement with the ring 14, a basin 25 is swingably mounted on the tank frame and thus adapted to be 20 moved in beneath the receptacle after the roller has been raised nearly through the receptacle. The composition falling into the basin drains back into the tank 15.

In operation of the apparatus above described, 25 the roller to be coated is first coupled to the cable 7 and, by rotation of the drum 10 in the proper direction under the control of a motor switch 26, is lowered through the receptacle 6 into a pit 27. The direction of the motor drive 30 is then reversed and the roller raised until the upper end engages the underside of the ring 14 and raises the same slightly as shown in Fig. 2 whereupon the motor is stopped. The pump 16 is then started and the flow of composition into 35 the receptacle adjusted until an excess of composition continues to overflow into the pipe 23.

Next, the motor is started in a direction to raise the roller. As the roller is thus drawn upwardly through the layer of molten composition, the successive longitudinal sections thereof are exposed to the composition for equal intervals of time and a film thereof adheres to the roller surface. The heat imparted to the roller by the composition is returned to the composition 45 on the surface prolonging the downward draining along that portion of the roller surface disposed above the level in the receptacle. But, owing to the uniformity of heating produced as above described, such draining takes place approximately uniformly throughout the length of 50 the roller leaving a film of uniform thickness as the composition congeals in cooling.

As the lower end of the roller approaches the ring 14, the basin 25 is swung in beneath the 55 roller so as to catch the composition discharged from the receptacle as the lower end of the roller passes out of contact with the ring. The entire surface of the roller will then be coated and the roller may be swung to one side and stood 60 on end to permit draining of the composition down the roller to continue until the film has congealed.

I claim as my invention:

1. In a machine of the character described, an 65 upwardly opening receptacle having a bottom opening adapted to be closed by a roller to be coated when the latter extends in a vertical direction through the opening, an inlet for said receptacle opening near the bottom thereof, an 70 overflow outlet opening for the receptacle disposed above said inlet opening, means for supplying molten composition to said inlet at a

substantially constant rate of flow sufficient to maintain an overflow from said outlet, and power driven means for raising said roller at a uniform speed whereby to present successive longitudinal sections of the roller to the layer of composition in said receptacle. 5

2. In a machine of the character described, an upwardly opening receptacle having a bottom opening adapted to be closed by a roller to be coated when the latter extends in a vertical direction through the opening, means to supply molten composition to said receptacle at a rate in excess of the amount required for coating a roller, an overflow outlet for withdrawing molten composition from the top of the body of composition in 15 said receptacle whereby to maintain a substantially constant liquid level therein, and means for effecting relative vertical movement between said roller and said receptacle at a substantially uniform speed and in a direction to expose successive longitudinal sections of the roller to said composition beginning at the upper end of the roller. 20

3. In a machine of the character described, a tank for containing a supply of molten composition and having an outlet near the bottom thereof, a receptacle having a bottom opening adapted to receive a roller with its axis in vertical position, an overflow outlet within said receptacle, means operable to withdraw composition from 25 said tank below the level of liquid therein and deliver the same to said receptacle below the level of said outlet and at a rate of flow such as to maintain a flow of liquid through said outlet, and means for raising said roller through the receptacle at a substantially uniform speed. 30

4. Apparatus for coating a roller with printers' composition comprising means to support the roller with its axis in upright position, a receptacle adapted to contain a body of molten composition contacting the surface of said roller 40 around the entire periphery thereof, means for effecting relative movement between said body of composition and said roller in a direction endwise of the latter, a tank for storing molten composition, means operating to withdraw composition from said tank below the level therein and deliver the composition to said receptacle below the level of the composition in the latter, an overflow outlet for said receptacle operable during 45 coating of the roller to remove air cells accumulating at the surface of the composition in the receptacle, and means for returning the overflow to said tank. 50

5. Apparatus for coating a roller with printers' composition comprising means to support the roller with its axis in upright position, a receptacle adapted to contain a body of molten composition contacting the surface of the roller around the entire periphery thereof, means for effecting relative movement between said body of 60 composition and said roller in a direction endwise of the latter, means operable during at least a part of said relative movement to deliver molten composition to said receptacle at a point below the level of the composition therein, and an overflow outlet for said receptacle operable during the delivery of composition to the receptacle to remove composition from the surface of the body in 65 said receptacle and thereby withdraw the accumulating air cells from the coating retained on 70 the roller surface. 75
